UNITED STATES PATENT OFFICE

2,446,269

ELECTRODE MOUNTING STRUCTURE FOR
ELECTRON TUBES

Donald F. Drieschman, San Carlos, Calif., assignor to Eitel-McCullough, Inc., San Bruno, Calif., a corporation of California

Application May 8, 1945, Serial No. 592,542

6 Claims. (Cl. 250—27.5)

1

My invention relates to an electron tube particularly adapted for ultra high frequency operation.

It is among the objects of my invention to provide a tube of the character described having an improved construction of and arrangement for the electrodes in an envelope.

Another object is to provide improved supporting means for the electrodes, whereby the latter may be assembled with facility and to maintain close and accurate spacings between the electrode surfaces.

A further object is to provide a tube in which the exhaust tubulation is formed as an integral part of the anode.

The invention possesses other objects and features of advantage, some of which, with the foregoing, will be set forth in the following description of my invention. It is to be understood that I do not limit myself to this disclosure of species of my invention as I may adopt variant embodiments thereof within the scope of the claims.

Referring to the drawing:

The figure of the drawing is an axial sectional view of a tube embodying the improvements of my invention.

In terms of broad inclusion my tube comprises an anode, a concentric cathode stem, and an intermediate grid terminal, all arranged coaxially on an envelope. The anode has a portion projecting internally and another portion projecting externally of the envelope. An exhaust tubulation is arranged on the anode, communicating with a passage ported into the envelope. A cooler for the anode is carried by the externally projecting portion, and preferably surrounds the exhaust tubulation. Improvements are also provided in the cathode stem and grid mounting structures.

In greater detail, and referring to the drawing, my preferred tube comprises a cylindrical body section 2 of vitreous material, such as glass, sealed at one end to an anode supporting member 3 and at the other end to a grid terminal member 4. The anode support 3 is preferably a metal cup having a cylindrical wall 6 extending outwardly from base flange 7 to which the glass is sealed. An inwardly extending neck 8 on flange 7 provides the direct support for the anode.

The anode is preferably of a metal having good heat conductivity, such as copper, and comprises an inwardly projecting portion 9 having a flat end face 11 presented interiorly of the envelope. Heat is conducted away from the active anode surface 11 by outwardly projecting anode portion

2

12, which portion is preferably cylindrical and of sufficient cross-sectional area to provide for the necessary heat flow. The anode unit is secured to support 3 by suitable means, as by a copper braze 13 at the rim of neck 8.

The tube is exhausted through a metal tubulation 14 secured to the end of anode projection 12. This tubulation communicates with a passage 16 in the anode ported into the envelope through opening 17. After exhaust, the tube is sealed by mechanically pinching off the tubulation at tip 18. The above feature of exhausting the tube through the anode is very important because it removes the necessity of a tubulation at some other point on the envelope where it would unduly complicate the structure.

A suitable cooler is provided on the anode, preferably comprising a metal core 19 fitted on anode extension 12 and carrying a series of radiating fins 21. By surrounding tubulation 14, the cooler performs the additional function of providing a protective closure for the tubulation.

Grid terminal member 4 is in the nature of a metal tube arranged coaxial with the anode and having an outturned flange 22 to which glass body section 2 is sealed. Grid 23 of the tube is of the disk type having bars lying in a plane parallel to anode face 11. The grid is secured to the inner end of a mounting sleeve 24 which is adapted for insertion through the open end of tubular member 4, and is finally secured in place by spot welding to the reduced neck portion 26 of member 4. Since the outer end of the tubular member is open at this stage of assembly, the sleeve 24 may be accurately positioned by a suitable jig to obtain proper spacing between grid 23 and anode face 11. Member 4, being connected to grid 23, functions as a terminal for the grid.

Cathode stem 27 is also coaxial with the anode, and is arranged to project into tubular member 4. The stem comprises a pair of concentric stem members including an outer tubular part 28 and an inner rod-like part 29. These stem parts are joined together by a glass bead 31 sealed between rod 29 and the lower end of a sleeve 32, which sleeve is fitted into tubular stem part 28 and secured thereto by a braze 33. For convenience of making connections with the inner stem member, a cup-shaped terminal 34 is preferably fixed to the outer end of rod 29.

The cathode comprises a cylindrical can 36 having a flat top carrying the active cathode coating. This coating may be of the usual oxide type commonly employed with indirectly heated cathodes. Can 36 is supported by and electrically con-

connected to the outer stem member 28. The cathode heater comprises a spiral 35 having one end connected to the rim of outer stem member 28 and the other end connected to inner stem member 29. A sleeve 37 about the heater aids in directing heat toward the active surface of the cathode.

The cathode stem is supported by a U-shaped sleeve fitted into tubular member 4 and having an outer flange 38 and an inner flange 39. A vitreous ring or washer 41 is sealed between outer stem member 28 and inner flange 39 of the supporting sleeve. Accurate positioning of the cathode relative to the grid is achieved by abutting sleeve 38-39 with an outturned flange 42 on grid supporting sleeve 24. Sleeve 24 thus functions as a spacer and positioning stop for the cathode unit. Final braze 43 is made at the edge of flange 38 and the adjacent rim of tubular member 4.

It will be noted that the parts on my tube are so arranged that the anode, cathode stem, and intermediate grid terminal, are all coaxial. This feature is important from the standpoint of circuit connections.

I claim:

1. An electron tube comprising an envelope, a tubular metallic member forming part of the envelope, a metallic stem member projecting into the envelope through said tubular member, an electrode connected to the stem member, a metallic sleeve in the tubular member and secured thereto, a vitreous ring sealed between the stem member and said sleeve, a second metallic sleeve in the tubular member and secured thereto, and a second electrode in the envelope connected to said second sleeve, the second sleeve being seated against the first sleeve in said tubular member.

2. An electron tube comprising an envelope, a tubular metallic member forming part of the envelope, an outer metallic stem member projecting into the envelope through said tubular member, an inner metallic stem member concentric with said outer stem member, sealing means interposed between the stem members including a metallic sleeve projecting downwardly into the outer stem member, sealing means interposed between the outer stem member and said tubular member, and an electrode in the envelope connected to said stem members.

3. An electron tube comprising an envelope, a tubular member forming part of the envelope, a pair of abutting sleeves in the tubular member, an electrode in the envelope supported on one of the sleeves, and a second electrode in the envelope supported on the other sleeve.

4. An electron tube comprising an envelope, a tubular metallic member forming the lower portion of the envelope, an electrode in the envelope,

a support for the electrode comprising a metallic sleeve in the tubular member with a lower edge terminating adjacent the lower edge of said tubular member, said edge of the sleeve lying within the cylinder defined by the inner surface of the tubular member, and a fused metallic bond uniting said edges.

5. An electron tube comprising an envelope, a tubular metallic member forming the lower portion of the envelope, a metallic stem member projecting into the envelope through said tubular member, an electrode connected to the stem member, a metallic sleeve having an outer flange lying along the inner surface of the tubular member and having an inner flange spaced from said outer flange, said outer flange having a lower edge terminating adjacent the lower edge of the tubular member, said edge of the outer flange of the sleeve lying within the cylinder defined by the inner surface of the tubular member, a fused metallic bond uniting said edges, and a vitreous ring sealed between the stem member and the inner flange of said sleeve.

6. An electron tube comprising an envelope, a tubular metallic member forming the lower portion of the envelope, a metallic stem member projecting into the envelope through said tubular member, an electrode connected to the stem member, an inverted U-shaped metallic sleeve in the tubular member with the lower edge of its outer flange terminating adjacent the lower edge of said tubular member, said edge of the outer flange of the sleeve lying within the cylinder defined by the inner surface of the tubular member, a fused metallic bond uniting said edges, and a vitreous ring sealed between the stem member and the inner flange of said sleeve.
